HANDLE FOR KITCHEN UTENSILS OR SIMILAR ARTICLES

Robert Arthur Eckersberg, Chicago, Ill., assignor to Ekco Products Company, Chicago, Ill., a corporation of Delaware

Filed Dec. 8, 1960, Ser. No. 63,158

Term of patent 14 years

(Cl. D44—29)

Fig. 1 is a side elevational view of a handle for kitchen utensils showing my new design.

Fig. 2 is a top plan view thereof.

Fig. 3 is a bottom plan view.

Fig. 4 is a front end view.

Fig. 5 is a rear end view.

Fig. 6 is a sectional view taken along line 6—6 of Fig. 1.

I claim:

The ornamental design for a handle for kitchen utensils or similar articles, as shown.
